NOISELESS DUMB WAITER SYSTEM

Charles C. Lundberg, Brooklyn, and Fred E.
Sparring, New York, N. Y.

Application March 6, 1933, Serial No. 659,866

7 Claims. (Cl. 187—1)

This invention relates to a noiseless dumb waiter system and has for an object to provide an improved dumb waiter system that will be noiseless in operation.

5 A further object of this invention is to provide a dumb waiter system in which it will be impossible for either the dumb waiter or the counter weight to become disengaged from the guide or to become jammed on the guide.

10 A still further object of this invention is to provide a dumb waiter system which will have perfectly plumb guides thereby insuring smooth and easy running at all times.

A still further object of this invention is to 15 provide a noiseless dumb waiter system which may be installed more quickly and more easily than any present system and when installed will give better service and will last without repairs for the life of the building.

20 Still a further object of this invention is to provide a knock-down all metal dumb waiter which can be assembled on the job, saving time and storage space, and in which the knock-down unit occupies a minimum amount of space thereby making it less expensive to both ship and to store.

A still further object of this invention is to provide a dumb waiter which will be both fire proof and burglar proof.

25 A yet additional object of this invention is to provide a dumb waiter system wherein the dumb waiter is preferably made of metal but wherein the basic features of this system can likewise be applied to dumb waiters made of other materials, such as wood.

With the foregoing and other objects in view, as will hereinafter become apparent, this invention comprises the constructions, combinations and arrangements of parts, hereinafter set forth, disclosed and shown on the accompanying drawings. In the drawings,

Figure 1 is a vertical section through the dumb waiter shaft clearly showing the guides mounted thereon;

Figure 2 is a sectional view taken on the line 2—2 of Fig. 1;

Figure 3 is a sectional view taken on the line 3—3 of Fig. 1 showing the braces mounted on the dumb waiter;

Figure 4 is a sectional view taken on the line 4—4 of Fig. 1;

Figure 5 is a sectional view of one of the grease cups taken on the line 5—5 of Fig. 3;

Figure 6 is a sectional view taken on the line

6—6 of Fig. 2 clearly showing how the grease cup is fastened to the weight;

Figure 7 is a sectional view taken on the line 7—7 of Fig. 2; and

Figure 8 is a modification showing a guide clip 60 fastened to a wood dumb waiter.

There is shown at 10 a conventional dumb waiter shaft in which this improved dumb waiter system has been installed. The cap of the shaft 10 is covered by a sheet metal plate 11 which acts 65 as a support for the sheaves 12 and 13.

A pair of angle irons 14 and 15 are likewise supported across the top of the shaft 10 by projecting into the walls 16 on opposite sides of the shaft 10. Secured to angle irons 14 and 15 are 70 a plurality of eye bolts 17, there being two eye bolts on each angle iron and these eye bolts 17 serve as upper anchoring means for the guide cable 18 for the dumb waiter 19, and 20 for the counter weight 21, the cable guides 18 and 20 75 being secured to the eye bolts 17 by means of clamps 22.

Another pair of angle irons 23 and 24 are buried in a concrete foundation 25 after having first secured thereto a pair of eye bolts 26 secured to 80 each angle iron 23 and 24. The concrete foundation 25 is of a thickness equal to the length of the shanks of the eye bolts 26. The bottoms of the cables 18 and 20 are fastened by similar clamps 22 to eye bolts 27 forming part of the turn buckles 85 28, these turn buckles 28 having a J bolt 29 for securing the same to the eye bolts 26 which are secured to the angle irons 23 and 24. As will be apparent, cable guides 18 and 20 can be quickly and easily assembled or dis-assembled in operative position due to the structure just described, and the turn buckles 28 serve to place just the proper amount of tension in the cables 18 and 20 so that they will be perfectly plumb and all the slacks will be eliminated.

The dumb waiter 19 will preferably be all metal, being made of sheet metal or sheet iron sections and other metal units. The back and side walls 31 and 32 of the dumb waiter 19 are composed of a sheet metal member shaped as shown in 100 Figure 4, which is held between the top 33 and bottom 34 of the dumb waiter 19. The top and bottom members 33 and 34 are substantially identical, each being made of a sheet metal member having turned over edges 35 which receive and hold the upper and lower edges of the back and side walls 31 and 32. The back and side walls 31 and 32 thus act as a spacer member between the top 33 and bottom 34. A piece of tubing 36 extends to each of the four corners of the top 110

and bottom walls 33 and 34 the ends of the tubing 36 being studded as at 37 to receive nuts 38 thereover and thus hold the dumb waiter 19 in assembled position. A shelf 39 may be hinged 5 as at 40 to a ledge 41 secured by any suitable means to the back 31 of the dumb waiter 19. A pair of cross straps 42 are secured on top of the dumb waiter 19 by being placed over the studded ends 37 of the tubes 36 before the nuts 10 38 are placed in position, the cross point 43 being held spaced from the top 33 of the dumb waiter by means of a small section of tubing 44. An eye bolt 45 secured in the spacing tubing 44 serves to support the dumb waiter 19 on the lifting cable 15 46, the cable 46 passing over the sheaves 12 and 13 and is secured at its other end by means of an appropriate eye bolt 47 to the counter weight 21. The tubes 36 are hollow throughout and are of slightly greater internal diameter than the external diameter of the guide cable 18, the guide cable 18 being extended through two of the tubes 36 before they are secured in position. At the 20 upper end of these two guide receiving tubes 36 a grease cup 48 is studded onto the end 37 of the tube 36. The grease cup 48 consists of a tubular section 49, a cap end 50 studded at one end thereof and studded onto the tube 36 at a second cap end 51 having an aperture 52 allowing the cable 18 to pass therethrough. The grease cup 48 is kept filled with any suitable cup grease, 25 as at 53, it being only necessary to unthread the cap 51 to refill the grease cup 48. As will be obvious the guide cable 18 and the inside of the tube 36 will be kept thoroughly greased as the grease cup 48 travels up and down the cable 18. It will be understood, however, that although only 30 two cables 18 have been shown as passing through two of the tubes 36, it is within the purview of this invention that similar cables 18 and grease cups 48 may be provided for each of the additional tubes 36, if desired. The counter weight 21 is guided up and down the guide cables 20 by means of an upper guide clip 54 secured thereto by a bolt and nut 55 and lower guide clip 56 secured 35 thereto by a bolt and nut 55. The opposite ends of the upper guide clip 54 are formed into encircling bands 57 for holding grease cups 58, the grease cups 58 being similarly formed of a tube section 59 through which are threaded upper and lower cap sections 60 whereby they may be kept 40 filled with a suitable type of cup grease. The upper and lower cap sections 60 are each provided with an aperture 61 to permit the guide cables 20 to pass therethrough, thus keeping the guide 45 cable 20 properly greased at all times. The lower guide clip 56 is provided with a pair of turned over ends 62 within which the guide cable 20 passes, cable 20 having already been properly greased by passing through the grease cup 58 in the upper 50 guide clip 54.

As a result of the construction just described, the guide cables 18 and 20 are kept in a condition of proper lubrication thus insuring absolutely noiseless operation at all times. By suitably tightening the turn buckles 28, the guide cables 18 and 20 are kept absolutely plumb at 55 all times, thereby keeping the dumb waiter 19 and the counter weight 21 spaced away from the sides of the shaft a sufficient distance to guarantee against any contact between either the dumb waiter 19 or the counter weight 21 and the sides of the shaft, even though the sides of the shaft may become somewhat out of plumb due to cracking or settling. When the dumb waiter is made 60 of wood instead of in the preferred manner, as

above described, of metal, guide clips 66 are secured as at 67 to one of the walls 68 of the wooden dumb waiter, guide clips 66 being preferably of a substantial length up to the height of the dumbwaiter per se, and the ends thereof are turned over as at 68 to permit the guide cable 18 to move up and down therein. With this system the dumb waiter may be easily installed in the shaft without disturbing the shaft opening, it being only necessary to select a suitable size of dumb waiter 19 so that it may be installed clear of the sides 16 of the shaft 10, according to the manner above set forth.

As will be apparent from the above description, the entire dumb waiter system may be easily knocked down for storage or for shipment, occupying a minimum amount of space. The back walls 31 and side walls 32 serve as a container for the remainder of the equipment when storing or shipping the same.

The novel features and the operation of this device will be apparent from the foregoing description. While the device has been shown and the structure described in detail, it is obvious that this is not to be considered limited to the exact form disclosed and that changes may be made therein within the scope of what is claimed without departing from the spirit of the invention. Having thus set forth and disclosed the nature of this invention, what is claimed is:

1. In a dumb waiter system having a shaft, cable guide means anchored in said shaft and spaced from the sides of said shaft, a dumb waiter, and a plurality of tube means forming an integral part of said dumb waiter slidably receiving said cable guide means therethrough.

2. In a dumb waiter system having a shaft, cable guide means anchored in said shaft and spaced from the sides of said shaft, a dumb waiter, a plurality of tube means forming an integral part of said dumb waiter slidably receiving said cable guide means therethrough, and lubricating means secured on said cable receiving means continuously lubricating said cable guide means during operation.

3. In a dumb waiter system having a shaft, cable guide means anchored in said shaft and spaced from the sides of said shaft, a dumb waiter, means forming an integral part of said dumb waiter slidably receiving said cable guide means therethrough, said cable guide receiving means comprising one or more hollow tubes extending the height of the dumb waiter and located at the corners thereof.

4. In a dumb waiter system having a shaft, cable guide means anchored in said shaft and spaced from the sides of said shaft, a dumb waiter, means forming an integral part of said dumb waiter slidably receiving said cable guide means therethrough, said cable guide receiving means comprising one or more hollow tubes extending the height of the dumb waiter and located at the corners thereof, and a grease cup secured on each of said one or more cable guides receiving tubes and aligned therewith, causing said cable guides to lubricate itself and said hollow tubes during operation.

5. In a dumb waiter system, a knock-down metal dumb waiter, said dumb waiter comprising a back wall and two side walls, a top ceiling and a bottom floor, a flange depending from said top ceiling and a flange projecting upwardly from said bottom wall, said flanges embracing the back and side walls of said dumb waiter, a plurality of tube members connecting said top ceiling and

bottom floor together, said back wall and side wall members being between said tube members and said ceiling and floor flanges.

6. In a dumb waiter system, a knock-down 5 metal dumb waiter, said dumb waiter comprising a back wall and two side walls, a top ceiling and a bottom floor, a flange depending from said top ceiling and a flange projecting upwardly from said bottom wall, said flanges embracing the 10 back and side walls of said dumb waiter, a plurality of tube members connecting said top ceiling and bottom floor together, said back wall and side wall members being between said tube members and said ceiling and floor flanges, cable 15 guide means in said dumb waiter system, some of said tube members also serving to slidably receive said cable guide means therethrough.

7. In a dumb waiter system, a knock-down

metal dumb waiter, said dumb waiter comprising a back wall and two side walls, a top ceiling and a bottom floor, a flange depending from said top ceiling and a flange projecting upwardly from said bottom wall, said flanges embracing the 80 back and side walls of said dumb waiter, a plurality of tube members connecting said top ceiling and bottom floor together, said back wall and side wall members being between said tube members and said ceiling and floor flanges, cable 85 guide means in said dumb waiter system, some of said tube members also serving to slidably receive said cable guide means therethrough, and hollow grease cup members aligned with and secured to said cable guide means receiving tubes. 90
